United States Patent Office

Des. 185,804
Patented Aug. 4, 1959

185,804

GAME BOARD

Jesse L. Goodspeed, White Plains, N.Y.

Application May 15, 1958, Serial No. 50,906

Term of patent 3½ years

(Cl. D34—5)

The drawing is a face view of a game board embodying my new design.

The game board is of conventional thickness.

I claim:

The ornamental design for a game board, as shown and described.
